UNITED STATES PATENT OFFICE.

EMORY GLENN SIMPSON, CHARLES JOHN SCHMIDT, AND FRANK PHILIP CARSTENS,
OF DETROIT, MICHIGAN, ASSIGNEES TO TERNSTEDT MANUFACTURING COMPANY,
OF DETROIT, MICHIGAN, A CORPORATION OF MICHIGAN.

WINDOW-LIFTING APPARATUS.

1,343,410.

Specification of Letters Patent. Patented June 15, 1920.

Application filed October 1, 1919. Serial No. 327,680.

To all whom it may concern:

Be it known that we, EMORY GLENN SIMPSON, CHARLES J. SCHMIDT, and FRANK P. CARSTENS, citizens of the United States, 5 residing at Detroit, in the county of Wayne and State of Michigan, have invented certain new and useful Improvements in Window-Lifting Apparatus, of which the following is a specification.

10 This invention relates to window lifter stops. It is necessary in connection with the ordinary window lifter in a closed automobile body to provide some form of stop which will hold the window in its lifted 15 position at any point along its range of travel. This is usually accomplished by providing a locking device which is disengaged by the initial turning effort of the crank before the turning effort of the crank 20 takes effect upon the lifting mechanism.

It is the object of the present invention to provide a window lifter stop of quite a different type wherein no lost motion between the crank and lifting mechanism is required 25 to release the lock. The device operates simply on the principle of an irreversible drive. The parts are of such design that practically all of them can be made simply as stampings, which very materially reduces 30 the cost of manufacture.

In the drawings,—

Figure 1 is an inside elevation of the top parts of an ordinary window lifter.

Fig. 2 is a section on the line 2—2 of 35 Fig. 1.

Fig. 3 is a detail of the stop or the irreversible driving connection shown in non-active position.

Fig. 4 is a similar view showing how the 40 irreversible driving connection locks when turning effort is exerted by the tendency of the window to drop.

Fig. 5 is a similar view showing how the irreversible driving connection allows the 45 parts to rotate when the turning effort is exerted through the crank.

Fig. 6 is a section on the line 6—6 of 50 Fig. 3.

Fig. 7 is a perspective detail of the crank- 55 shaft.

Fig. 8 is a perspective detail of the driv- 60 ing disk.

Fig. 9 is an elevation of the spring disk.

The ordinary chain window-lift comprises a chain *a* running over a sprocket wheel *b*, 55 which is driven by a large gear wheel *c* that in turn is driven by a small pinion *d*. It has, heretofore, ordinarily been the practice to provide a lock between this pinion *d* and a stationary part of the casing *e*. A 60 little lost motion is provided between the crank and the driving pinion so that the initial movement of the crank in taking up this lost motion serves by a cam action to release the pinion from its locking engagement with the stationary part of the casing. 65

The present window-lifter stop operates on the principle of an irreversible driving connection between the crank and window-lifting mechanism. The crankshaft is des- 70 ignated *f* and is flattened at one end as at *g* to take the crank (not shown). The casing *h* is on its front face perforated as at *i* to receive the fingers *j* of the window-lifter stop box *k*. This serves to clamp the window-lifter-stop box *k* to the casing that houses the driving parts of the window-lift. This window-lifter-stop box is detailed sectionally in Fig. 6. A driving plate *l* of the peculiar shape shown in Figs. 3, 4 and 5, is 75 roughly of a double hour-glass shape, and is provided with four recesses *m* for the disks *n*. When the disks *n* are in repose, as shown in Fig. 3, at the bottom of the recesses *m*, there is a clearance between the disks and the box *k*. However, when an effort is made 80 to turn the driving plate *l* by applying the turning effort directly to the plate, the jammed condition shown in Fig. 4 results. 85

The outline of the driving plate leading 90 away from the bottom of the recess *m* is radially a slightly greater distance from the center than the bottom of the recess. Hence when the weight of the window tends to drive the pinion *d*, this pinion being in 95 driving connection with the driving plate through the pins *p*, the result portrayed in Fig. 4 occurs. The disks *n* which are on the forward side of the driving plate (considering that side forward which is forward 100 in the direction of turning) drop back into the bottoms of their recesses and clear the box *k*, but there is nothing to carry the other two disks *n* that lie at the rear of the driving plate around with the driving plate. 105 The inclined surfaces *o* leading out of the

recesses *m* wedge in under the ball and thereby jam them between the box and the driving plate. An effort to move the driving plate through the pinion in the opposite direction results in exactly the same jamming action except that the other two balls take part in the jamming instead of those mentioned.

When turning effort is communicated to the plate by the crankshaft a different action takes place. The crankshaft is provided with a flange or driving key *q*, which engages in a similar hole in the driving disk *r*. This driving disk is provided with a pair of struck-down lugs *s* that are adapted to engage between the disks *n* of the driving plate. If the turning effort is communicated to the crank, these driving lugs *s* drive the driving plate *l* through the rear disks *n*, as shown in Fig. 5. The forward disks are never in danger of jamming in between the driving plate and the box *k*. The rear disks cannot jam in between the driving plate and the box because they are carried along ahead of the driving lugs *s*. The consequence is that all the disks now clear the box and there is no jamming or locking action whatever. The same action takes place when the driving is done in the opposite direction.

t is a spring disk interposed between the driving disk *r* and the driving plate *l* for the purpose of taking up any side play and making the device rattle-proof. *u* is a counter-balancing spring housed between the gear *c* and the casing.

What we claim is:

1. In a window lift, the combination of means for lifting a window including a pinion, and an irreversible driving connection therefor which turns freely when actuated to turn the pinion but which locks when the pinion is turned to actuate the driving connection, said irreversible driving connection comprising a cylindrical box, an actuating member connected with the pinion and provided with recesses, rolling members engaging in said recesses, a second actuating member connected with a crankshaft and which can actuate the first actuating member by engaging the said rolling members, said recesses being so formed that an attempt to turn the first actuating member through the gear will thrust the rolling

members out to jam with the cylindrical box.

2. In a window lift, the combination of means for lifting a window including a pinion, an irreversible driving connection therefor, and a crankshaft for actuating the irreversible driving connection, the parts of said irreversible driving connection thrusting radially outward and jamming when actuation is attempted through the pinion while the parts operate freely with clearance when actuation is through the crankshaft.

3. In a window lift, the combination of means for lifting a window including a pinion, a cylindrical box supported adjacent thereto, a crankshaft running through the box, a disk *r* provided with lugs and which is coupled up in driving relation with the crankshaft, a driving plate *l* that is coupled up with the said pinion to drive therewith, the said driving plate and driving disk being located in said box and the driving plate being provided with recesses, and rolling members adapted to engage in said recesses which are arranged to provide cam surfaces to thrust the rolling members into jammed relation with the cylindrical box when actuation is from the driving plate but which said rolling members remain in their recesses and allow the driving plate to rotate freely when actuation is through the driving disk *r*.

4. In a window lift, the combination of means for raising and lowering a window including a rotating member and a crank, and a clutch for holding the window at any desired position in its travel, comprising a stationary member surrounding the parts that rotate and that can also be thrust radially outward, said parts being so arranged that actuation thereof by the raising and lowering of the window thrusts them outwardly and jams them against the stationary member to prevent operation while rotation of the parts through the crank keeps the parts in radially retracted position and allows free rotation to raise and lower the window.

In testimony whereof we affix our signatures.

EMORY GLENN SIMPSON.
CHARLES JOHN SCHMIDT.
FRANK PHILIP CARSTENS.
